UNITED STATES PATENT OFFICE.

HERBERT T. REESE, OF SPRINGFIELD, OHIO, ASSIGNOR TO THE SPRINGFIELD METALIC CASKET COMPANY, OF SPRINGFIELD, OHIO, A CORPORATION OF OHIO.

BURIAL-VAULT.

1,092,289.

Specification of Letters Patent.

Patented Apr. 7, 1914.

Application filed August 25, 1913. Serial No. 786,581.

To all whom it may concern:

Be it known that I, HERBERT T. REESE, a citizen of the United States, residing at Springfield, in the county of Clark and State 5 of Ohio, have invented certain new and useful Improvements in Burial-Vaults, of which the following is a specification.

My invention relates to improvements in closures for metallic grave vaults, and more 10 especially to the construction of the locking bolts of such devices.

The object of the invention is to provide a bolt which is not only adapted for locking the closure in position but which may also 15 be utilized for clamping the closure firmly to the casing so as to provide a water tight joint; the particular object being to provide a bolt which will adjust itself to any irregularities in the surface of the part against 20 which it is clamped, and also a bolt which will be adapted to adjust itself to curved surfaces.

The invention consists in the constructions and combinations of parts hereinafter 25 described and set forth in the claims.

In the accompanying drawings,—Figure 1 is a vertical section through the vault, showing the inner side of the door of the vault and the locking mechanism, said locking 30 mechanism being in unlocking position and embodying the features of my improvement. Fig. 2 is a vertical section on the line 2—2 of Fig. 1. Fig. 3 is a transverse section on the line 3—3 of Fig. 1. Fig. 4 is a detail of 35 one of the locking bolts and a portion of the casing shown in section, the bolt being shown in locking position. Fig. 5 is a section on the line y—y of Fig. 4. Fig. 6 is a detail of a part of the locking mechanism.

40 Like parts are represented by similar characters of reference in the several views.

In the locking mechanism for vaults of the character to which this invention relates, it has been common to provide a series of locking 45 bolts, in the nature of locking frames, generally four in number, one respectively for the top, bottom and sides. These locking frames have been provided with a series of bolts proper and means have been provided 50 for projecting the frames to locking position and then tilting or swinging the frames to clamping position to draw the parts together so as to provide a water tight joint. Difficulty has been experienced however in 55 causing all of the bolts proper of any frame

to clamp with equal pressure upon the rim of the casing, because of irregularity in the construction, and more especially at the top of the casing because of the fact that the top is generally formed of a rounding nature or 60 on the arc of a circle; this difficulty having been due to the fact that heretofore the locking frames have been constructed of a rigid nature which would prevent the respective bolts proper, of any one frame, from adjusting 65 themselves to the irregular surface or to the curvature of the surface. Before describing in detail the improved construction of the locking bolt, an explanation will first be made of the manner of operating these 70 bolts to locking and clamping position.

In the said drawings, 1 represents the vault casing, which has near the open end thereof an inturned flange 2.

The door of the vault is represented by 3, 75 and may be of any usual construction and is adapted to close the open end of the structure. Screw-threaded in a centrally arranged thimble 4 secured to the door 3, is a sleeve 5, having a squared outer end 5^a to 80 receive a wrench or other tool. Journaled in the screw-threaded sleeve 5 is a shaft 6, also having a squared outer end 6^a to receive a wrench or other tool, and having secured to its inner end a collar 7 to which is made fast 85 a pinion 8. The teeth of the pinion 8 are in mesh with the teeth of a series of four cam wheels 9, 10, 11 and 12, journaled to the arms of a spider 13, loosely mounted upon the unthreaded end 5^b of the screw-threaded sleeve 90 5. Each of these cam wheels has a cam groove 14 which receive projecting pins 15 on the inner ends of a series of four locking bolts or frames 17, 18, 19 and 20. The bolts proper 21, of these locking frames, project 95 through a series of clips or keepers 22, pivotally connected to rods 23, 24, 25 and 26, which rods are supported at their respective ends in ears 27 projecting from the door. Each of the locking bolts is provided at its 100 inner end with a slot 28 into which projects a pin 29 on the outer end of each of the arms of the spider 13, and in order that the inner end of the locking frames may be held in position on these pins, there are provided two 105 cross bars 30 and 31, of a resilient nature, each of which is perforated at its respective ends to receive the pins 29, and are held in position by cotter pins 32, the said bars crossing each other and bearing against the 110

- inner end of the collar 7; these cross bars also serving to brace the arms of the spider when the parts are operated in the manner hereinafter described.
- 5 The operation is as follows: The door having been placed in position against the vault, with a gasket or packing 33 between its edge and the flange 2, the shaft 6 is revolved, thus revolving the cam wheels 9, 10, 10 11 and 12, through the medium of the pinion 8. This projects all the locking bolts outwardly in line with the flange 2. The screw-threaded sleeve 5 is next revolved, which forces all the parts to the position 15 shown in Fig. 2, whereupon, the keepers 22, acting as fulcrums, the outer ends of the bolts will be caused to impinge against the inner side of the flange 2, thus clamping the door firmly in position against the packing.
- 20 Secured to the collar 7 is a second collar 34, having a perforated enlargement 34¹ in which is located a plunger 35, having thereon a coil spring 36 interposed between the enlargement and a small pin 37; this plunger 25 being normally held in retracted position by a cotter pin 38, placed in a perforation in the flange on the inner side of the enlargement. Before the door is placed in position, this cotter pin 38 is removed, the outer end of the plunger extending into a 30 perforation in the pinion 8. Located at a suitable point in the spider is a perforation 39, and so soon as the plunger coincides with this perforation 39, it will be forced into same and thus lock the shaft 6 against revolution to prevent the withdrawal of the 35 bolts. Means are also provided for locking the bolts in their tilted position so as to prevent the unclamping of the same, which, 40 while not permitting access to the vault, would nevertheless result in destroying the water-tight joint. Pivoted at 42 to inwardly extending ears on the door, is a series of shouldered locking fingers 40, one for each 45 locking frame, which fingers normally project through perforations 43 in the frames, as shown in Fig. 3. As the frames are tilted to their clamping position, these fingers will be drawn by springs 41 to cause the shouldered portions thereof to engage the frames 50 and thus lock them from return movement, as shown in Figs. 2 and 3.
- It will be observed that the top of the vault and the inturned flange 2 projecting 55 from said top, are formed on the arc of a circle, so as to form a rounded top for the vault, which is the usual construction of devices of this kind. It will also be observed that it is necessary to arrange the respective 60 bolts 21 of the frame 17 at different angles with respect to each other so that their outer ends will be at different distances from the pin 15, which is the point at which the power is applied to tilt the frame. If the 65 frame was a rigid one, it will be seen that
- when the same was tilted to clamping position the inner bolts of the frame would be the first to contact the rim 2, inasmuch as all of the bolts project at the same angle from the frame, and that no clamping effect whatever would be obtained from the outside and intermediate bolts. To overcome this difficulty, I have constructed the frame 17 in two parts, 17^a and 17^b, the pin 15 serving to connect the parts together; the respective members of said frame being provided with perforated ears 17^c, for the purpose, the perforations in said ears being somewhat larger than the diameter of the pin so as to provide for a loose fit. The member 17^b also preferably has a projecting guide 17^d, having an inturned end adapted to embrace a portion of the frame-member 17^a so as to further assist in holding the respective members of the frame together but permitting a movement of the same with respect to each other. The result of this construction is, that as the frame is tilted, the contact of the inner bolts proper with the flange 2 will cause the frame to bow at the center sufficiently to permit the outer and intermediate bolts to also contact the flange 2 and thus cause all of the bolts of this frame 17 to clamp the door to the flange uniformly throughout the entire width of the top. The other locking frames may also be constructed in two parts, but in the present case I have shown but one of them, the lower one, so formed. While the lower flange 2 is formed on a straight line and consequently there would not be the same necessity of dividing this lower locking frame, yet in some cases, due to faulty construction, these flanges 2 are irregular in contour. 90
- The construction of the lower frame 19 is 95 the same as that of the upper frame, with the exception that the bolts all project at the same angle, but by forming this frame in two parts, these bolts will be permitted to seat themselves more uniformly on the flange 2, if for any reason there should be any irregularity in the construction of the same. 100
- Having thus described my invention, I 105 claim:—
1. In a vault closure, the combination, with a door and a casing having an inwardly extending rim, locking mechanism carried by said door comprising in part a series of locking frames, one or more of said frames 110 being constructed in two sections flexibly connected together, and means for moving said locking frames to locking position over said rim and for causing the same to impinge said rim. 115
  2. In a vault closure, the combination, with a door and a casing having an inwardly extending rim, a locking mechanism consisting in part of a series of locking frames, one or more of said locking frames being 120

formed in two sections with a series of bolts on each of said sections, said sections being flexibly connected together, and means for throwing said locking frames to locking position and for causing the same to impinge said rim.

3. In a vault closure, the combination with a door and a casing having an inwardly extending rim having one of its sides formed 10 on the arc of a circle, a locking mechanism consisting in part of a series of locking frames, the locking frame corresponding to the curved part of the rim being formed in two sections flexibly connected together, and 15 means for throwing said locking frame to locking position over said curved rim and for tilting the same to clamping position.

4. In a vault closure, the combination, with a door and a casing, an inwardly ex-

tending rim on said casing having one of its 20 sides formed on the arc of a circle, a locking mechanism consisting in part of a series of locking frames, the locking frame corresponding to the curved part of said rim being formed in two sections flexibly connected 25 together, a series of bolts on said last mentioned locking frame formed rigid therewith and projecting in different directions, and means for throwing said frame to locking position to cause said bolts to extend over 30 said curved rim and for causing said bolts to impinge said rim.

In testimony whereof, I have hereunto set my hand this 22nd day of August 1913.

HERBERT T. REESE.
